UNITED STATES PATENT OFFICE.

HARRISON VAN SCOY, OF ADDISON, NEW YORK.

FIRE-ESCAPE.

SPECIFICATION forming part of Letters Patent No. 425,716, dated April 15, 1890.

Application filed January 13, 1890. Serial No. 336,773. (No model.)

To all whom it may concern:

Be it known that I, HARRISON VAN SCOY, a citizen of the United States, residing at Addison, in the county of Steuben and State of New York, have invented a new and useful 5 Fire-Escape, of which the following is a specification.

This invention relates to fire-escapes of that class more particularly known as "friction;" 10 and the same consists, broadly, of a body or shank having a T-head provided with perforations, a pin through said shank, and a band or girth for inclosing the body of the user and connected to the lower end of the shank. 15 In carrying out the invention the same also consists of specific details of construction—as, for instance, the manner of passing the rope through the head and shank and around the pin—all as will be hereinafter described. 20 In the accompanying drawings, Figure 1 is a general side elevation of my device, showing it in its operative position and its rope leading from the window of a house. Fig. 2 is an enlarged perspective view of the device 25 proper. Fig. 3 is a similar view showing a different arrangement of stringing. Fig. 4 is an edge view.

To a hook *w* or to another equivalent support within the room of a house is secured a 30 rope *R*, which, in event of an alarm of fire, is thrown from the window *W*, and upon this rope is mounted my frictional fire-escape, as will be understood.

The user, having swung herself or himself 35 from the window, with the girth *A* around his waist or connected to his person in any suitable manner, grasps the friction device proper and operates the same to exert a certain friction upon the rope *R* in the course of his descent, in order that the latter may not be too rapid and that the user will not come in too violent contact with the ground. Of course the user may carry parcels or a small child in his unemployed hand or arm, and, if desired, 45 even a third person may descend at the same time by resting one foot upon the upper end of the device and holding the rope *R* between his hands. This latter expedient will, however, rarely be necessary, because when the 50 device has reached the lower end of the rope and the user has disengaged the same from

his person it may be drawn up again by any other person who will pull upon the rope, and can be set in position for a second or subsequent descent, the same as in the first instance. Many devices for accomplishing the above results have heretofore been made, and I will now proceed to describe the manner in which my improved fire-escape is constructed.

The letter *S* designates a vertical shank, preferably of hard wood, and to the lower end of this shank a metallic strap *V* is secured by means of bolts or rivets *v* passing through the strap and the body of the shank. The 65 strap *V* at its lower end extends slightly beyond the end of the shank, and a ring *I* is preferably inserted therein, into which the snap-hook *N* upon the girth *A* may be engaged. The said girth is constructed in any 70 suitable manner, preferably of strap with a buckle *K*, by means of which it may be adjusted in size.

At the upper end of the shank *S* and securely fastened thereon is a flat metallic 75 plate *H*, provided with holes *h* near each end and rounded edges *C* opposite one of said holes, all as shown in Figs. 2 and 3, and this plate stands preferably at right angles to the shank *S*, whereby in side elevation the entire 80 device will be of approximate T shape, the plate *H* representing the head. Below this plate *H* at some distance, and in the same plane therewith, the shank is provided with a transverse hole *s*, and still farther below 85 this a strong metallic pin *P* is rigidly secured through the shank at right angles to the plane of the hole *s* and the head *H*, said pin having an enlarged head *p* at one end, as best shown in Fig. 4. With this construction 90 the rope *R* is passed first downwardly through one of the holes *h* in the head *H*, thence through the transverse hole *s* in the shank *S*, thence again upwardly through the other hole *h*, thence bent over into one of the rounded 95 corners *C* and downwardly to the ground. This manner of stringing will give a certain amount of friction, which will perhaps be sufficient where a small child or person of very light weight is being lowered to the 100 ground, and it will be understood that if a person standing on the ground draw tightly

on the depending end of the rope the friction will be increased and the speed of descent of the person supported by the device will be correspondingly decreased.

- 5 In Fig. 2 I have illustrated another form of stringing, wherein the rope R, after having been passed through the rounded corner C, is given a single or perhaps a double turn around the shank of the pin P below its head 10 p, and this manner of stringing will of course cause a considerable increase in the friction, thereby adapting the device for supporting a person of much heavier weight, but must generally be operated by the person seated 15 in the girth A, who will with one hand grasp the shank S and retain the coil of the rope R upon the pin P.

In Fig. 3 I have shown still another form of stringing, wherein the free end of the rope 20 is passed below the pin P on one side of the shank, thence around the shank, and finally over the pin on the opposite side of the shank; but this manner of stringing is only another of the various modifications therein and variations 25 in the manner of imparting a greater or less degree of friction to the rope, according as the weight of the person descending on the device may require.

Having thus described my invention, what 30 I claim is—

1. The herein-described fire-escape, the same comprising a shank S, provided with a hole s, and a T-head H, provided with vertical holes h h, the corners of said head opposite one of said holes h being rounded, as at C, in combination with the rope R, passing downwardly through one of said holes, thence through the hole in the shank, then upwardly to the other of said holes, and thence led outwardly over one of said rounded corners and downwardly, and friction devices, substantially as described, engaging the free end of the rope below said rounded holes, as set forth.
- 40 2. The herein-described fire-escape, the

same comprising a shank S, provided with a hole s, a T-head H, provided with vertical holes h h, the corners of said head opposite one of said holes being rounded, as at C, and a headed pin P, passing through said shank, 50 in combination with the rope R, passing downwardly through one of said holes h, thence through the hole in the shank, thence upwardly through the other of said holes, and thence led outwardly over one of said rounded 55 corners and its free end frictionally engaged with said pin, substantially as set forth.

3. The herein-described fire-escape, the same comprising a shank S, provided with a lateral hole s, a T-head H in the same plane 60 with said lateral hole, said head being provided with the vertical holes h h, and its corners opposite one of said holes being rounded, as at C, a pin P, passing through said shank below the hole s therein and at right angles 65 to the plane of said hole, the shank of said pin being rigidly secured in the shank and one end thereof provided with an enlarged head p, the strap V, rigidly secured to the lower end of the shank S and carrying the 70 ring I, and the adjustable girth A, removably connected to said ring, in combination with the rope R, its upper end connected to a suitable support, and its body passing downwardly through one of the holes in the head, 75 laterally through the hole in the shank, thence upwardly through the other hole in the head, and thence outwardly over one of said rounded corners, downwardly and into frictional engagement with said pin, and thence 80 downwardly to the ground, the whole constructed and adapted for use substantially as set forth.

In testimony that I claim the foregoing as my own I have hereto affixed my signature in 85 presence of two witnesses.

HARRISON VAN SCOY.
